Attorneys,*

UNITED STATES PATENT OFFICE.

FRED ARN, OF CHATTANOOGA, TENNESSEE, ASSIGNOR TO J. M. CARD LUMBER CO., OF CHATTANOOGA, TENNESSEE, A CORPORATION OF TENNESSEE.

CHOCK BLOCK.

1,403,535.

Specification of Letters Patent. Patented Jan. 17, 1922.

Application filed April 13, 1920. Serial No. 373,517.

To all whom it may concern:

Be it known that I, FRED ARN, a citizen of the United States, and resident of Chattanooga, county of Hamilton, State of Tennessee, have invented certain new and useful Improvements in Chock Blocks, of which the following is a specification.

My invention relates to chock blocks used in transporting automobiles for holding them on the car floor.

One object of my invention is to provide a block which is capable of being made at a high rate of production, will provide means whereby the nails which are employed for affixing the block to the floor, may be readily positioned to be driven substantially perpendicular to the floor and which will permit the hammer blows to be applied without requiring unusual care or skill on the part of the workman, and will present a large surface area on its bottom face for contact with the floor and will have an extending rear heel portion providing a bearing part well in the rear of the upper portion of the block.

The invention is shown in the accompanying drawings in which:—

Figure 1 is a side elevation of the block and

Fig. 2 a perspective view.

These blocks are made from wooden timbers, they are of solid formation and are of such form that they can be expeditiously produced. Each block comprises vertical sides 1, a base 2 and a curved front face 3, which is grooved lengthwise so as to conform substantially to the curve of the tire of the wheel which is to be chocked by the block. The block has a vertical rear face 5 and an extension 6 at the lower portion of this vertical rear face, said extension projecting rearwardly therefrom. The upper face of this extension is substantially horizontal or it may incline slightly downward towards the rear and through this heel extension the nails are inserted for attaching the block to the car floor. This rear extension is entirely beyond or in the rear of the vertical rear face of the block and its extent is such that the nails may be inserted through this extension in a substantially perpendicular position to the floor, and by reason of the fact that the space above the upper surface of the extension is entirely free and unobstructed, the workman can

with facility and rapidity apply the hammer blows for driving the nail through the block and through the floor of the car on which the automobile is to be transported. This rear extension also provides an addition to the lower or base face of the block so that the lower face which comes in contact with the floor of the car will be of considerable area and will thus have a better holding effect or contact with the car floor. 60 This rear heel extension will also provide a bearing well towards the rear of the vertical face and the top of the block so that it will be impossible for the block to tip up towards the rear under the pressure from the 70 wheel of the automobile. Ordinarily the pull on an automobile chock block is such that there is a tendency to draw out the nails if these are driven in diagonally or in other words inclined downwardly and towards the front of the block. It has been found in tests that the perpendicular nail has the greatest strength and holding power, and the extension heel on the present block enables the nail to be driven in a position 75 80 perpendicular to the floor.

One advantage of the present construction is that although the block is provided with a rear extension for receiving the nails in substantially perpendicular position the 85 block is light in weight, because of the material which is cut out in forming the vertical face and the extension heel. It will be obvious that if the extension were made by inclining the rear face from the upper 90 edge of the block to the rearmost point, for instance, along the dotted line α , α in Figure 1, the material left in the space y would add to the weight of the block and when it is considered that these blocks are made in 95 enormous quantities and shipped in car load lots, the comparatively small saving in weight in each individual block constitutes a great saving in weight and in material when it is considered that these blocks are 100 made and shipped in the large quantities mentioned.

I claim as my invention:

A chock block for automobiles consisting of a solid piece of wood having a horizontal 105 lower face and a curved front face, a rear face and a heel extension at the lower portion of the rear face projecting rearwardly therefrom beyond the rearmost vertical plane touching said rear face and in line 110

with the general length of the block, the said heel extension presenting an upper face extending clear across the block from one side to the other with an unobstructed free
5 space vertically above it extending clear to the top of the block so that the nails can be readily driven through the heel exten-

sion, the said upper face of the heel extension terminating at a point above the plane of the lower face of the block substantially 10 as described.

In testimony whereof, I affix my signature.

FRED ARN.
